UNITED STATES PATENT OFFICE

145,880

DESIGN FOR AN AIRPLANE

Bert G. Carlson, Gates Mills, Ohio, assignor, by
mesne assignments, to Jack & Heintz Precision
Industries, Inc., Cleveland, Ohio, a corporation
of Delaware

Application March 24, 1945, Serial No. 118,662

Term of patent 3½ years

(Cl. D71—1)

To all whom it may concern:

Be it known that I, Bert G. Carlson, a citizen
of the United States, residing at Gates Mills,
in the county of Cuyahoga and State of Ohio,
have invented a new, original, and ornamental
Design for an Airplane, of which the following is
a specification, reference being had to the ac-
companying drawings, forming part thereof,
herein:

Figure 1 is a side elevational view of an air-
plane showing my new design;

Figure 2 is a top plan view;

Figure 3 is a front elevational view thereof;
and

Figure 4 is a bottom plan view thereof.

The opposite side of the airplane is the same
as that shown in Figure 1 with the exception that
the door is omitted.

I claim:

The ornamental design for an airplane, sub-
stantially as shown and described.

BERT G. CARLSON.
